UNITED STATES PATENT OFFICE.

DAVID HILLIS, OF DES MOINES, IOWA.

AIRSHIP.

971,379.

Specification of Letters Patent. Patented Sept. 27, 1910.

Application filed December 20, 1909. Serial No. 534,019.

To all whom it may concern:

Be it known that I, DAVID HILLIS, a citizen of the United States, residing at Des Moines, in the county of Polk and State of Iowa, have invented a new and useful Airship, of which the following is a specification.

The object of this invention is to provide improved means for supporting and driving 10 a conveyance or vehicle in and through the air.

A further object of this invention is to provide improved means susceptible of operation in a given direction and serving the 15 dual purpose of supporting and progressing a conveyance or vehicle in and through the air.

My invention consists in the construction, arrangement and combination of elements 20 hereinafter set forth, pointed out in my claims and illustrated by the accompanying drawing, in which—

Figure 1 is a side elevation of the complete apparatus. Fig. 2 is a front elevation of 25 the same.

In the construction of the device as shown the numeral 10 designates a platform on which is mounted a motor 11. The platform also is adapted to support and carry 30 passengers, operatives or merchandise. Standards 12, 13 are arranged in converging planes on and rise from one side of the platform 10. The standards 12, 13 are connected by a cross bar 14 at their upper ends 35 and preferably below their centers, dotted lines Fig. 2. Standards 16, 17 are mounted in converging planes on and rise from the platform 10 at the opposite side thereof from the standards 12, 13 and preferably 40 parallel therewith. The standards 16, 17 are connected at their upper ends by a cross bar 18 parallel with the bar 14 and are further connected intermediate of their ends and preferably below their centers by a cross 45 bar 19 (dotted lines Fig. 2) parallel with the bar 15. Bars 20, 21 are mounted across and connect end portions of the bars 14, 18 and extend materially beyond them at each end. Bars 22, 23 extend across and connect 50 the standards 12—16 and 13—17 respectively coincident with the bars 15, 19 and extend materially beyond them at each end.

An end frame is provided and is formed of standards 24, 25 in converging planes and parallel with the standards 12, 13, an upper 55 cross bar 26 parallel with the cross bar 14 connecting the upper ends of said standards 24, 25, and a lower cross bar 27 parallel with the cross bar 15 and connecting the lower ends of said standards 24, 25. The end 60 frame is mounted on and fixed to end portions of the bars 20, 21, 22 and 23.

The end frame just described is spaced apart from the standards 12, 13 and cross bars 14, 15 a distance approximating to the 65 width of the platform 10.

Another end frame of identical construction with the first end frame and designated in Fig. 2 by the numeral 28 applied to one of its standards and the numeral 29 applied 70 to its upper cross bar, is provided and is supported by the opposite end portions of the bars 20, 21, 22, 23. The latter end frame is parallel with and spaced from the standards 16, 17 and cross bars 18, 19 a distance 75 approximating to the width of the platform 10.

Plate journal bearings 30, 31, 32 and 33 are provided and are located centrally in the spaces described as follows: The plate 80 30 is located in the space inclosed by the standards 12, 13 and cross bars 14, 15; the plate 31 is located in the space inclosed by the standards 16, 17 and cross bars 18, 19; the plate 32 is located in the space inclosed 85 by the first end frame having the standards 24, 25 and cross bars 26, 27; and the plate 33 is located in the space inclosed by the second end frame having the standard 28 and cross bar 29. The plate journal bearings 30, 31, 32 and 33 are supported by arms or spokes of like construction and illustrated in Fig. 1 and designated as 34, 35, 36, 37, 38, 39, 40 and 41, which arms or spokes are connected at their inner ends to the 95 plates and extend to or across the various standards and cross bars and are connected thereto. Arms 38, 39 on the plates 30, 31 extend and are connected to the platform 10 between the primary standards of the 100 frame.

A shaft 42 is mounted for rotation in the plate journal bearings 30, 31, 32, 33 and is driven by a pulley 43 thereon, which pulley

is connected by a belt 44 to the motor 11. Four sets of spokes are fixed to and radiate from the shaft 42 and are arranged in pairs between end frames and primary frames of the structure. One set of these spokes is shown in Fig. 1 and the individuals thereof are designated by the numerals 45, 46, 47, 48, 49, 50, 51 and 52. Four rims 53, of like construction, are mounted on the sets of 10 spokes 45-52 inclusive and said rims are connected in pairs by sets of counter-shafts (eight for each rim). One set of counter-shafts is illustrated in Fig. 1 and designated by the numerals 54, 55, 56, 57, 58, 59, 60 and 15 61. Two sets of vanes are mounted on the counter-shafts 54-61 inclusive and one set thereof is illustrated in Fig. 1 and designated by the numerals 62, 63, 64, 65, 66, 67, 68 and 69. Each vane extends equally on opposite 20 sides of its counter-shaft and is arranged at right angles thereto and is so fixed that it will revolve only with said shaft. One or more arms are fixed to end portions of each counter-shaft and extend at right angles to 25 and equal distances from said counter-shaft. One set of these arms is illustrated in Fig. 1 and designated by the numerals 70, 71, 72, 73, 74, 75, 76, and 77. Each arm 70-77 inclusive is provided with anti-friction rollers 30 78, 79 on its end portions and projecting laterally therefrom. The anti-friction rollers preferably project outwardly from extreme or outer faces of the arms 70-77 inclusive. Two or more tracks are employed, 35 one pair of tracks for each set of arms 70-77 inclusive. One pair of these tracks is illustrated in Fig. 1 and is composed of four separate cams or sections designated by the numerals 80, 81, 82 and 83. Each cam or 40 section is curved irregularly throughout its length; that is to say, its contour employs arcs of different radii and different centers. It is the function of the cam 80 to receive and provide on its inner surface a track for 45 the anti-friction rollers on the arms 70-77 inclusive and by so doing limit oscillation of said arms in one direction. It is the function of the cam 81 to receive and provide on its outer surface a track for the anti-friction 50 rollers on the arms 70-77 inclusive and limit oscillation of said arms in one direction. The cams 80, 81 conjunctively provide the outermost track or controlling means for the arms 70-77 inclusive and generally form 55 semi-annular portions of said track of irregular contour, each end portion of each cam 80 overlying or communicating with the adjacent end portion of a cam 81. It is the function of the cam 82 to receive and 60 provide on its inner surface a track for the anti-friction rollers on the arms 70-77 inclusive opposite to the rollers being engaged by the cam 80 and limit oscillation of said arms in the direction opposite to the limit imposed by said cam 80. It is the function 65 of the cam 83 to receive and provide on its outer surface a track for the anti-friction rollers on the arms 70-77 inclusive opposite to those rollers engaged by the cam 81 and to limit oscillation of said arms in a direction 70 opposite to the limit imposed by said cam 81. The cams 82, 83 form an inner track for the anti-friction rollers and generally provide semi-annular portions of said track of irregular contour. The cams 82, 83 are conjunctively arranged eccentric to the conjunctive arrangement of the cams 80, 81. Adjacent end portions of the cams 82, 83, at one end each, overlap and are spaced apart and oppositely beveled in order that successive 75 rollers may ride from the outer surface of the cam 83 to the inner surface of the cam 82. Opposite end portions of the cams 82, 83 are spaced apart and arranged in such manner that successive rollers may ride from the inner surface of the cam 82 to the inner surface of a cam 80 and thence to the outer surface of a cam 81, while the alternate successive rollers on successive arms may ride from the inner surface of a cam 80 to the 80 outer surface of a cam 83. This arrangement of cams, rollers, arms and vanes provides for the support of the vanes at various and constantly changing angles relative to each other and relative to any line extending 85 radially from the shaft 42. The arrangement is such that in the rotation of the shaft 42 and consequent travel of the vanes through their common orbit said vanes breast the air when they are above and in front of the shaft 42 and feather to the air when they are below and at the rear of said shaft. The result of such arrangement is that the vanes above and in front of the shaft tend to lift the apparatus in the air while the vanes below said shaft tend to advance or propel the apparatus through the air and the vanes at the rear of the shaft feather to the air and have no perceptible effect in raising or propelling the apparatus. This statement 90 should be modified to the extent of saying that when vanes are in the position shown by those designated by the numerals 68, 69 they do have some effect in buoying the apparatus since they are inclined from the vertical in the direction of travel of the apparatus and receive somewhat of the lifting effect of the air through which they move. 95 The machine may be equipped with a single set of arms 70-77 inclusive for each set 100 of counter-shafts 54-61 inclusive, and in such event they would be provided with one set of cams 80-83 inclusive for each set of arms. 105 The apparatus may be caused to ascend by 110 placing movable ballast, such as passengers, 115 120 125

on that portion of the platform 10 adjacent to the motor 11, or in other words on the rear portion of the platform. The apparatus may be caused to descend by placing the movable ballast, such as passengers, on the forward portion of the platform 10.

The apparatus may be steered in either direction to the right or left by shifting the movable ballast to the right or left side of the platform 10.

In operation each vane makes one-half a rotation on its axis in each revolution of the wheel; hence the rotation of the vanes on independent axes is in the ratio of one to two to the travel of the vanes through the common orbit.

I claim as my invention—

1. An air-ship, comprising a platform, primary frames thereon, end frames parallel with and carried by the primary frames, a shaft journaled in said frames, wheels on said shaft, feathering vanes on said wheels, tracks on said frames controlling said feathering vanes, said tracks formed with irregular curves and arranged in eccentric positions and each track composed of disconnected cams, and a motor on said platform geared to said shaft.

2. An air-ship, comprising a platform, primary frames fixed to and rising from said platform, end frames parallel with and carried by the primary frames, a shaft mounted for rotation in said frames and adapted to be geared to a prime mover on the platform, wheels on said shaft, feathering vanes on said wheels, arms on said vanes, and disconnected, irregularly-curved and inter-communicating tracks on said frames adapted for engagement by said arms.

3. In an air-ship, a wheel formed with feathering vanes, said vanes adapted for travel through a common orbit and also adapted for rotation on independent axes, the rotation of the vanes on independent axes being in the ratio of one to two to the travel of the vanes through the common orbit; the rotation controlling means comprising arms on said vanes and outer and inner tracks engaged by said arms, the outer tracks each composed of irregularly-curved cams overlapping and spaced apart at one end and spaced as to continuity at the opposite end, the inner tracks eccentric to the outer tracks and each composed of irregularly-curved cams spaced radially and also spaced as to continuity at each end.

4. In an air-ship, a wheel formed with feathering vanes, said vanes adapted for travel through a common orbit and also adapted for rotation on independent axes, the rotation of the vanes on independent axes being in the ratio of one to two to the travel of the vanes through the common orbit, the

rotation controlling means comprising arms on said vanes perpendicular to and crossing the planes of the vanes and outer and inner tracks engaged by said arms, the outer tracks each composed of irregularly-curved cams overlapping and spaced apart at one end and spaced as to continuity at the opposite end, the inner tracks eccentric to the outer tracks and each composed of irregularly-curved cams spaced radially and also spaced as to continuity at each end.

5. In an air-ship, a wheel formed with feathering vanes, said vanes adapted for travel through a common orbit and also adapted for rotation on independent axes, the rotation of the vanes on independent axes being in the ratio of one to two to the travel of the vanes through the common orbit, the rotation controlling means comprising arms on said vanes and outer and inner tracks engaged by said arms, the outer tracks each composed of irregularly-curved cams overlapping and spaced apart at one end and spaced as to continuity at the opposite end, the inner tracks eccentric to the outer tracks and each composed of irregularly-curved cams spaced radially and also spaced as to continuity at each end, opposite ends of each arm adapted for alternate engagement with and travel on opposite faces of track cams and of alternate tracks.

6. In an air-ship, a wheel formed with feathering vanes, said vanes adapted for travel through a common orbit and also adapted for rotation on independent axes, the rotation of the vanes on independent axes being in the ratio of one to two to the travel of the vanes through the common orbit, the rotation controlling means comprising arms on said vanes and outer and inner tracks engaged by said arms, the outer tracks each composed of irregularly-curved cams overlapping and spaced apart at one end and spaced as to continuity at the opposite end, the inner tracks eccentric to the outer tracks and each composed of irregularly-curved cams spaced radially and also spaced as to continuity at each end, each end of each arm in traversing an orbit successively engaging and traveling on the inner face of one outer-track cam, the outer face of one inner-track cam, the inner face of the other inner-track cam, the inner face of the terminal portion of the first mentioned outer-track cam and the outer face of the other outer-track cam.

7. In an air-ship, a wheel formed with feathering vanes, said vanes adapted for travel through a common orbit and also adapted for rotation on independent axes, the rotation of the vanes on independent axes being in the ratio of one to two to the travel of the vanes through the common

orbit, the rotation controlling means comprising arms on said vanes, said arms of approximately the same length as the width of the vanes and arranged perpendicular to and crossing the planes of said vanes, and outer and inner tracks engaged by said arms, the outer tracks each composed of irregularly-curved cams overlapping and spaced apart at one end and spaced as to

continuity at the opposite end, the inner 10 tracks eccentric to the outer tracks and each composed of irregularly-curved cams spaced radially and also spaced as to continuity at each end.

DAVID HILLIS.
